UNITED STATES PATENT OFFICE

2,293,004

PHOTOGRAPHIC COLOR PICTURE

Hermann Lohaus, Dessau, Germany, assignor, by
mesne assignments, to General Aniline & Film
Corporation, New York, N. Y., a corporation of
Delaware

No Drawing. Application April 1, 1939, Serial No.
265,601. In Germany April 7, 1938

21 Claims. (Cl. 95—6)

My present invention relates to the manufacture of photographic color pictures.

It is known to produce photographic color pictures with the aid of color development by using in the developer or in the photographic layer a dyestuff former which during the development is oxidized together with the developing substance at the places containing the silver image to produce the dyestuff. As dyestuff formers for this color development there have been proposed phenols, naphthols, aniline, naphthylamine, aminonaphthols and compounds having a reactive methylene group.

One object of my invention is to provide as the dyestuff former a simple or substituted hydroxy-pyridine.

Another object of this invention is to provide as the dyestuff former a compound with a condensed pyridine ring system having in the pyridine nucleus one or several hydroxy groups.

Further objects of the invention will appear more in detail hereinafter.

The dyestuff former used according to the invention may be substituted in the pyridine ring or in the condensed ring or rings in any desired manner. Examples of compounds suitable for the invention are 3-hydroxypyridine, 2,6-dihydroxypyridine, 1-phenyl-6-hydroxy-2-pyridine, 4-hydroxyisoquinoline, 1-(4'-carbethoxy-phenyl)-4-methyl-6-hydroxy-2-pyridone.

These dyestuff formers may be added either to the developer or to the emulsion. With color developers, for example para-phenylenediamine or a derivative thereof blue or blue-violet dyestuff images are obtained.

When the dyestuff formers are added to photographic layers it is recommended that they should be made fast to diffusion in respect to the binding agent of the layer by the introduction of special groups. As groups of this kind there may be used those named in the British patent specification No. 488,048 and in the U. S. Patents 2,178,612, 2,179,238, 2,186,849, 2,186,850, 2,179,244, 2,186,732, 2,186,733, 2,156,821, 2,186,851, 2,186,735, 2,186,734, 2,186,719, 2,186,852, 2,154,918, 2,186,736 and 2,200,306. The group which renders the dyestuff former fast to diffusion may be introduced into its molecule in a manner in itself known by way of an amino group or a carboxyl group present in the nucleus an acid amide being formed. A radicle may alternatively be united directly to the nucleus. Dyestuff formers having groups which lend fastness to diffusion are for example 1-octodecyl-4-methyl-6-hydroxy-2-pyridone, 1-(4'-benzoylaminodiphenyl)-

4-methyl-6-hydroxy-2-pyridone. The silver halide emulsion having the dyestuff former fast to diffusion may be made into a photographic layer in the known manner and there may be one or several layers on one or both sides of a support superimposed on each other. The layers may be used for taking black and white pictures or color pictures. For the purpose of color photography the emulsion layers are preferably sensitized for different regions of the spectrum. If desired several dyestuff formers may be contained in one layer and these may be so selected that on development a neutral grey picture is produced.

15 The emulsion layers may also be made in other manner, for example differently sensitized emulsions with different dyestuff formers may be distributed in the form of small particles on a support.

20 The color picture may be produced in various ways for example in the manner described in any one of the U. S. Patents 2,179,228, 2,179,238, 2,186,849, 2,178,612 and 2,186,730. In the exposed emulsion layers the pictures may be developed by simple color development or by reversal development, as described in U. S. Patents 2,229,137 and 2,179,234.

25 In the production of black and white pictures by this invention the silver may be removed from the silver halide emulsion layer or the silver may be allowed to remain in the layer together with the dyestuff picture.

30 The following examples illustrate the invention:

35 *Example 1.*—To 1 kilo of a silver halide emulsion there are added 5 grams of 3-hydroxypyridine and the emulsion is cast to form a layer. After exposure development with para-dimethylaminoaniline produces a blue dyestuff image.

40 *Example 2.*—To 1 kilo of a silver halide emulsion there are added 5 grams of 2,6-dihydroxypyridine. This emulsion is cast to form a layer. After exposure development with para-dimethylaminoaniline produces a blue dyestuff image.

45 *Example 3.*—To 1 kilo of silver halide emulsion there are added 5 grams of 1-phenyl-4-methyl-6-hydroxy-2-pyridone of the formula

55 and the emulsion is cast to form a layer. After exposure and development with para-dimethyl-

aminoaniline a blue-violet dyestuff image is obtained.

Example 4.—1 mol of β -methyl-glutaconic acid is melted together with 1 mol of para-amino-benzoic acid ethylester and the mass is dissolved in methanol. From the solution 1-(4'-carbethoxy-phenyl)-4-methyl-6-hydroxy-2-pyridone of the formula

crystallizes.

5 grams of this compound are added to 1 kilo of the silver halide emulsion and this is cast to form a layer. After exposure and development with para-dimethylaminoaniline a blue dyestuff image is obtained.

Example 5.—1 mol of β -methyl-glutaconic acid is melted together with 1 mol of stearylamine and the mass is dissolved in methanol. From the solution 1-octadecyl-4-methyl-6-hydroxy-2-pyridone of the formula

crystallizes.

5 grams of this compound are added to 1 mol of the silver halide emulsion and this is cast to form a layer. After exposure and development with para-dimethylaminoaniline a blue-violet dyestuff image is obtained.

Example 6.—To 1 kilo of a silver halide emulsion there is added 1,3-dihydroxy-isoquinoline homo-phthalimide of the formula

in the form of a sodium salt in a quantity of 5 grams and the emulsion is cast to form a layer. After exposure and development with para-dimethylaminoaniline a blue dyestuff image is obtained.

Example 7.—To 1 kilo of the silver halide emulsion there are added 5 grams of the sodium salt of 1,4-diphenyl-6-hydroxy-2-pyridone of the formula

and the emulsions cast form a layer. After exposure and development with para-dimethylaminoaniline a blue dyestuff image is obtained.

Example 8.—1 mol of β -methyl-glutaconic acid is melted together with 1 mol of benzidine. The obtained 1-(4'-amino-diphenyl)-4-methyl-6-hydroxy-2-pyridone of the formula

is recrystallized from methanol. 5 grams of this compound are added to 1 kilo of a silver halide emulsion and this is cast to form a layer. After exposure development with para-dimethylaminoaniline produces a blue dyestuff image.

Example 9.—The 1-(4'-aminodiphenyl)-4-methyl-6-hydroxy-2-pyridone made as described in Example 8 is dissolved in dilute caustic soda lye and to the solution benzoyl chloride is added by drops. 1-(4'-benzoylaminodiphenyl)-4-methyl-6-hydroxy-2-pyridone of the formula

is precipitated. It is filtered with suction and washed. 5 grams of this compound are added to 1 kilo of the silver halide emulsion and this is cast to form a layer. After exposure and development with para-dimethylaminoaniline a blue dyestuff image is obtained.

Example 10.—To 1 kilo of a silver halide emulsion there are added 5 grams of 1-butyl-4-methyl-6-hydroxy-2-pyridone. The emulsion is then cast to form a layer. After exposure development with para-dimethylaminoaniline yields a blue dyestuff image.

Example 11.—To 1 kilo of a silver halide emulsion there are added 5 grams of 1-hexyl-4-methyl-6-hydroxy-2-pyridone. The emulsion is then cast to form a layer. After exposure development with para-dimethylaminoaniline yields a blue dyestuff image.

Example 12.—To 1 kilo of a silver halide emulsion there are added 5 grams of 1-octyl-4-methyl-6-hydroxy-2-pyridone. The emulsion is then cast to form a layer. After exposure development with para-dimethylaminoaniline yields a blue dyestuff image.

Example 13.—To 1 kilo of a silver halide emulsion there are added 5 grams of 1-dodecyl-4-methyl-6-hydroxy-2-pyridone. The emulsion is then cast to form a layer. After exposure development with para-dimethylaminoaniline yields a blue dyestuff image.

Example 14.—To 1 kilo of a silver halide emulsion there are added 5 grams of 1-cyclohexyl-4-methyl-6-hydroxy-2-pyridone. The emulsion is then cast to form a layer. After exposure development with para-dimethylaminoaniline yields a blue dyestuff image.

Example 15.—To 1 kilo of a silver halide emulsion there are added 5 grams of 1-methyl-4-phenyl-6-hydroxy-2-pyridone. The emulsion is then cast to form a layer. After exposure development with para-dimethylaminoaniline yields a blue dyestuff image.

Example 16.—To 1 kilo of a silver halide emulsion there are added 5 grams of 1-butyl-4-phenyl-6-hydroxy-2-pyridone. The emulsion is then cast to form a layer. After exposure development with para-dimethylaminoaniline yields a blue dyestuff image.

Example 17.—To 1 kilo of a silver halide emulsion there are added 5 grams of 1-hexyl-4-phenyl-6-hydroxy-2-pyridone. The emulsion is then cast to form a layer. After exposure development with para-dimethylaminoaniline yields a blue dyestuff image.

Example 18.—To 1 kilo of a silver halide emulsion there are added 5 grams of 1-octyl-4-phenyl-6-hydroxy-2-pyridone. The emulsion is then cast to form a layer. After exposure development with para-dimethylaminoaniline yields a blue dyestuff image.

Example 19.—To 1 kilo of a silver halide emulsion there are added 5 grams of 1-dodecyl-4-phenyl-6-hydroxy-2-pyridone. The emulsion is

then cast to form a layer. After exposure development with para-dimethylaminoaniline yields a blue dyestuff image.

Example 20.—To 1 kilo of a silver halide emulsion there are added 5 grams of 1-cyclohexyl-4-phenyl-6-hydroxy-2-pyridone. The emulsion is then cast to form a layer. After exposure development with para-dimethylaminoaniline yields a blue dyestuff image.

Example 21.—To 1 kilo of a silver halide emulsion there are added 5 grams of 1-carboxyl-phenylene-4-phenyl-6-hydroxy-2-pyridone corresponding with the following formula

The emulsion is then cast to form a layer. After exposure development with para-dimethylaminoaniline yields a blue dyestuff image.

Example 22.—To 1 kilo of a silver halide emulsion there are added 5 grams of 1,4-dihydroxy-3-carbethoxy-isoquinoline corresponding with the following formula

The emulsion is then cast to form a layer. After exposure development with para-dimethylaminoaniline yields a blue dyestuff image.

I claim:

1. In a process of producing photographic color pictures by dyestuff forming development, the improvement which comprises developing the exposed photographic silver halide emulsion with an aromatic amino developer containing as the dyestuff former a compound selected from the class consisting of hydroxypyridines and hydroxy-2-pyridones in which the N-atom is tertiary.

2. In a process of producing photographic color pictures by dyestuff forming developing, the improvement which comprises exposing a photographic silver halide emulsion containing as the dyestuff former a compound selected from the class consisting of hydroxypyridines and hydroxy-2-pyridones in which the ring N-atom is tertiary and developing said emulsion with an aromatic amino developer.

3. In a process of producing photographic color pictures by dyestuff forming development, the improvement which comprises exposing a photographic silver halide emulsion containing as the dyestuff former a compound selected from the class consisting of hydroxypyridines and hydroxy-2-pyridones in which the ring N-atom is tertiary, said compound containing a radicle imparting thereto fastness to diffusion with respect to the binding agent of said emulsion, and developing said emulsion with an aromatic amino developer.

4. Silver halide emulsion for color photography containing as a color forming component a compound selected from the class consisting of hydroxypyridines and hydroxy-2-pyridones in which the ring N-atom is tertiary, said compound containing a radicle imparting thereto

fastness to diffusion with respect to the binding agent of said emulsion.

5. A dyestuff forming developer comprising an aqueous solution containing an aromatic amino developing agent and a compound selected from the class consisting of hydroxypyridines and hydroxy-2-pyridones in which the ring N-atom is tertiary.

6. Silver halide emulsions for color photography containing as a color forming component a compound selected from the class consisting of hydroxypyridines and hydroxy-2-pyridones in which the ring N-atom is tertiary.

7. The silver halide emulsion defined in claim 15, 4, wherein the radicle imparting fastness to diffusion is a long aliphatic chain.

8. The silver halide emulsion defined in claim 4, wherein the radicle imparting fastness to diffusion is linked to the compound by a linkage selected from the class consisting of an acid amide linkage, a direct nuclear carbon to carbon linkage and a direct nuclear nitrogen to carbon linkage.

9. In the process of producing photographic colored pictures by dyestuff forming development, the improvement which comprises developing an exposed photographic silver halide emulsion with an aromatic amino developer in the presence of a color former selected from the class consisting of hydroxypyridines and hydroxy-2-pyridones in which the ring N-atom is tertiary.

10. The process as defined in claim 9 wherein 35 said ring N-atom is substituted by a substituent selected from the class consisting of alkyl, cyclohexyl, a phenyl, and a diphenyl radical.

11. The process as defined in claim 2 in which 40 said ring N-atom is substituted by a substituent selected from the class consisting of alkyl, cyclohexyl, a phenyl and a diphenyl radical.

12. The composition as defined in claim 6 wherein said ring N-atom is substituted by a substituent selected from the class consisting of alkyl, cyclohexyl, a phenyl and a diphenyl radical.

13. The composition as defined in claim 4 wherein said ring N-atom is substituted by a substituent selected from the class consisting of alkyl, cyclohexyl, a phenyl and a diphenyl radical.

14. The process as defined in claim 9 wherein 50 said ring N-atom is substituted by an alkyl radical containing up to eighteen carbon atoms.

15. The composition as defined in claim 4 wherein 55 said ring N-atom is substituted by an alkyl radical containing up to eighteen carbon atoms.

16. The process as defined in claim 9 wherein the color former is 1-octadecyl-4-methyl-6-hydroxy-2-pyridone.

17. The process as defined in claim 10 wherein 60 said color former is 1-(4'-amino-diphenyl)-4-methyl-6-hydroxy-2-pyridone.

18. The process as defined in claim 9 wherein 65 said color former is 1-octyl-4-methyl-6-hydroxy-2-pyridone.

19. The composition as defined in claim 4 wherein 70 said color former is 1-octadecyl-4-methyl-6-hydroxy-2-pyridone.

20. The composition as defined in claim 4 wherein 75 said color former is 1-(4'-amino-diphenyl)-4-methyl-6-hydroxy-2-pyridone.

21. The composition as defined in claim 4 wherein said color former is 1-octyl-4-methyl-6-hydroxy-2-pyridone.

CERTIFICATE OF CORRECTION.

Patent No. 2,293,004.

August 11, 1942.

HERMANN LOHAUS.

It is hereby certified that error appears in the printed specification of the above numbered patent requiring correction as follows: Page 3, first column, line 48, claim 1, before "N-atom" insert --ring--; and second column, line 13, for "atoms" read --atom--; line 60, for "claim 10" read --claim 9--; and that the said Letters Patent should be read with this correction therein that the same may conform to the record of the case in the Patent Office.

Signed and sealed this 9th day of March, A. D. 1943.

Henry Van Arsdale,

(Seal) Acting Commissioner of Patents.
